[57] CLAIM

The ornamental design for a converter for receiving signals from a satellite antenna, as shown and described.

DESCRIPTION

FIG. 1 is a left side elevational view of a converter for receiving signals from a satellite antenna with the dashed lines illustrating a support for the converter and an antenna, both of which do not form part of the present design but are shown for environmental purposes only;

FIG. 2 is a top plan view thereof;

FIG. 3 is a front elevational view thereof on an enlarged scale;

FIG. 4 is a right side elevational view thereof;

FIG. 5 is a rear elevational view thereof; and,

FIG. 6 is a bottom plan view thereof.
